UNITED STATES PATENT OFFICE.

NEWTON K. BOWMAN, OF NORTH LAWRENCE, OHIO.

MINING-MACHINE BIT.

Application filed January 26, 1921. Serial No. 440,120.

To all whom it may concern:

Be it known that I, NEWTON K. BOWMAN, citizen of the United States, residing at North Lawrence, in the county of Stark and 5 State of Ohio, have invented certain new and useful Improvements in Mining-Machine Bits, of which the following is a specification.

This invention relates to an improved 10 mining machine bit and has as one of its principal objects to provide a device of this character employing a demountable cutting tooth of hardened material and wherein the tooth will be of such construction as to present sharp cutting surfaces to the face of the 15 mine.

The invention has as a further object to provide a bit which may be readily employed in connection with the customary 20 links of a mining machine chain and wherein in the cutting tooth may be removed without difficulty.

And the invention has as a still further 25 object to provide a bit wherein the cutting tooth may be tightly clamped in position and wherein said tooth will be rigidly supported for engagement with the work.

Other and incidental objects will appear hereinafter.

30 In the drawing:

Figure 1 is a fragmentary plan view showing my improved bit in connection with two of the links of a mining machine chain of conventional construction.

35 Figure 2 is an enlarged sectional view showing one of the links in detail and illustrating the mounting of the bit thereon, and

Figure 3 is a detail perspective view showing the parts of the bit disassembled.

40 Referring now more particularly to the drawing, I have, in Figure 1, shown a portion of a conventional mining machine chain at 10 and, as usual, this chain is provided with links 11, the bit of the present invention being particularly designed for use in connection with a link of the type illustrated.

In Figure 2, one of the links is illustrated 45 in detail and, as will be observed, said link is formed with a recess 12 having an inclined bottom wall 13 and threaded through the front wall of said recess is a set screw 14. Intersecting said recess is an angularly disposed opening 15 through the link. The top 55 wall of this opening is formed by an abutment web 16 prolonged to define a nose over-

hanging the recess and formed on said web as well as the nose is a series of teeth 17. In carrying the invention into effect, I employ a bit holder or stock 18 which fits 60 freely in the opening 15 of the link and is provided at its upper side with teeth 19 meshing with the teeth 17 of the abutment web 16, the stock being formed with a beveled upper end face 20. Near its outer 65 end, the stock is cut away at its lower side to provide a seat 21 substantially V-shaped in cross section and having diverging flat side faces while at the inner end of said seat is defined an oblique shoulder 22. Fitting 70 freely in the recess 12 is a wedge 23 having an oblique bottom face 24 seating flat against the wall 13 of said recess to coact therewith while at its outer side the wedge is provided with a vertical face 25 confronting the inner 75 end of the set screw 14. Formed upon the inner side of the wedge near its upper end is a reentrant or female seat 26 which, like the male seat 21 of the stock, is substantially 80 V-shaped in cross section and is provided with flat side faces. Below the seat 26 the wedge is provided with an oblique face 27 adapted to seat flat against the lower side of the stock, mating therewith, and, as will be noted, the face 27 is offset with respect to the seat 26, an oblique shoulder 28 being defined 85 between said seat and face. This shoulder is disposed to abut the shoulder 22 of the stock, mating therewith.

A straight cutting tooth 29 is employed. 90 This cutting tooth is formed of hardened material and is substantially V-shaped in cross section, the tooth having flat diverging sides defining, at the forward side of the tooth, a cutting edge 30 extending from end to end of the tooth. At each end, the tooth is beveled to define a cutting prow terminating 95 in a cutting point 31 and having diverging cutting edges 32. The tooth is formed to fit over the seat 21 of the stock, the sides of the tooth seating flat against the side faces of said seat and the apex of the seat abutting the crotch between said sides so that the tooth will thus be rigidly supported 100 from end to end thereof. As will be noted, the seat 26 of the wedge 23 is formed to fit over the tooth, the sides of said seat seating flat against the sides of the tooth. Consequently, as will be seen, when the set screw 14 is turned for advancing the wedge in the 105 direction of the stock, the wedge will operate to firmly bind the tooth between said 110

- wedge and the stock. At the same time, the wedge will also act to hold the teeth of the stock in engagement with the teeth 17 of the web 16 of the link so that the stock will be locked against longitudinal movement, the face 27 of the wedge seating flat against the lower side of the stock and the shoulder 28 of the wedge seating flat against the shoulder 22 of the stock. As will be observed, the beveled ends of the tooth 29 are inclined to conform to the inclination of the face 20 and shoulder 22 of the stock so that when the tooth is in position, the beveled end of the tooth disposed upwardly for engagement with the work, will overlie and protect the stock, while the beveled end of the tooth disposed downwardly will abut the shoulder 22 seating flat thereagainst for sustaining the tooth against downward movement. The tooth will accordingly be supported both as against side strain as well as end thrust. By loosening the set screw 14 slightly so as to release the tension of the wedge upon the tooth, the tooth may be pulled upwardly and removed. As will be perceived, this operation of removing the tooth may be readily accomplished and particular attention is directed to the fact that to so remove the tooth it is unnecessary to displace the wedge or displace the stock. In a similar manner, the tooth may, of course, also be replaced and after one end of the tooth has become dull, the tooth may be turned end for end.
- 35 In use, the cutting point 31 of the exposed prow of the tooth will first enter the work for loosening the coal when the cutting edges 32 of said prow will cut through the loosened coal with a shearing action, the cutting edge 30 leading the cutting edges 32 so that these latter edges will always operate against loosened coal. Accordingly, as has been proven, in actual practice, much less power will be required to drive a bit of the present character as compared with an ordinary bit so constructed as to merely gouge into or mash the coal of the face of the mine as the bit is advanced. Furthermore, as the ends of the tooth wear away the presence of the cutting edge 30 will serve to maintain the cutting points 31 of the tooth sharp while wear upon the beveled end faces of the sides of the tooth will also tend to maintain the cutting edges 32 sharp as the tooth wears away. I accordingly provide a tooth of highly efficient design.
- Having thus described the invention, what is claimed as new is:
1. A bit for mining machines including a stock, a wedge binding the stock stationary, and a cutting tooth clamped between the stock and wedge engaged by the wedge.
  2. A bit for mining machines including a stock, a wedge binding the stock stationary, and a cutting tooth clamped between the stock and wedge engaged by the wedge.
  3. A bit for mining machines including a stock, a wedge binding the stock stationary, and a substantially V-shaped cutting tooth clamped between the stock and wedge and provided with beveled ends. 70
  4. A bit for mining machines including a stock, a wedge binding the stock stationary, and a double-ended cutting tooth clamped between the stock and wedge and provided with beveled ends, the tooth being reversible end for end upon the stock. 75
  5. A bit for mining machines including a stock, a wedge coacting therewith, and a substantially V-shaped cutting tooth clamped between the stock and wedge and provided with beveled ends, the stock being provided with an inclined shoulder and one end of the tooth abutting said shoulder. 80
  6. A bit for mining machines including a stock having a substantially V-shaped seat, a wedge binding the stock stationary and provided with a substantially V-shaped seat, and a substantially V-shaped cutting tooth fitting said seats and clamped therebetween. 85
  7. A bit for mining machines including a stock having a seat and formed at the inner end of said seat with an inclined shoulder, a wedge coacting with the stock and formed with an inclined face to abut said shoulder, and a cutting tooth clamped between the wedge and said seat resting at one end against the shoulder. 90
  8. The combination with a mining machine chain link having a recess and further provided with an opening having a wall thereof provided with teeth, of a stock disposed in said opening and provided with teeth to coact with said first mentioned teeth, a wedge disposed in said recess to coact with the stock, and a cutting tooth clamped between the wedges and stock. 105
  9. The combination with a mining machine chain link having a recess intersected by an opening, the recess being formed with an inclined bottom wall and a wall of the opening being provided with teeth, and a set screw adjustable upon the link to project into said recess, of a stock disposed in said opening and provided with teeth to coact with said first mentioned teeth, a wedge disposed in said recess to coact with the stock and engageable by said set screw, the wedge being provided with an inclined face to coact with the bottom wall of said recess, and a cutting tooth disposed between the stock and wedge, the set screw being adjustable to advance the wedge for binding the teeth of the stock in engagement with said first mentioned teeth and clamping the cutting tooth between the wedge and stock. 115
  10. The combination with a mining ma- 120
  11. A bit for mining machines including a stock, a wedge binding the stock stationary, and a cutting tooth clamped between the stock and wedge engaged by the wedge. 125
  12. A bit for mining machines including a stock, a wedge binding the stock stationary, and a cutting tooth clamped between the stock and wedge engaged by the wedge.

chine chain link, of a stock mounted upon the link, a wedge binding the stock in engagement with the link, and a cutting tooth clamped between the wedge and stock.

5 11. As a new article of manufacture, a double-ended reversible mining machine cutting tooth straight from end to end and having angularly disposed sides, the ends

of the tooth being beveled and the beveled ends thereof converging in the direction of 16 the free edges of said sides to define terminal cutting points at the plane of the junction between the sides.

In testimony whereof I affix my signature.

NEWTON K. BOWMAN. [L.S.]
